UNITED STATES PATENT OFFICE

LEWEY C. CARROLL, OF BRISTOL, VIRGINIA

PARQUETRY BALING MACHINE

Application filed August 2, 1929. Serial No. 383,038.

This invention relates to parquetry baling machines, and it consists in the novel features hereinafter described and claimed.

An object of the invention is to provide a machine of the character stated which is of simple and durable structure, easy to operate, and which may be conveniently and quickly used for tying a stack or bundle of strips or layers of parquetry, so that the said material may be easily handled, transported or stored preparatory to setting or laying in a floor.

A further object of the invention is to provide novel means for assembling the strips of parquetry in the form of a bundle.

A still further object of this invention is to provide novel means for applying a binding tape to the bundle of parquetry, said means adapted to be used for drawing the tape tightly around the bundle.

Still another object of the invention is to provide novel means for cutting or severing the tape after it has been drawn taut around the bundle.

Other and further objects will be made manifest as the description of the invention progresses.

In the accompanying drawings:

Figure 1 is a side elevation partly in section of the improved apparatus;

Figure 2 is a plan view;

Figure 3 is an end elevation;

Figure 4 is an enlarged detail of the means for applying and severing the binding element.

Figure 5 is a plan view of the structure shown in Figure 4.

Figures 6 and 7 and 8 are perspective details of a plurality of the binder stretching and severing members;

Figure 9 is a rear end elevation;

Figure 10 is an enlarged detail of the tape severing mechanism;

Figure 11 is a rear elevation of the structure shown in Figure 10.

The improved apparatus comprises a supporting frame including spaced vertical members 10 and longitudinal members 11, spaced below the upper ends of the vertical members 10, with the portion above, one of the longitudinal members connected by a side plate 12.

Disposed between the side members 10 and 12 is a platform member 14 having depending ends 15 bearing against the confronting faces of the vertical members 10. The platform 14 is adjustable vertically by any suitable means, for instance by slots 16 in the depending portions 15 and held by clamp screws 17. By this means the platform 14 may be adjusted vertically to adapt it to different sizes of the goods to be bound.

The longitudinal members 11 are each extended at one end beyond the members 10 and mounted in these extended ends is a shaft 18, and mounted to swing on this shaft is a lever arm 19.

Attached to the inner face of the lever arm is a bearing plate 20 having a vertical guide-way 21 in its upper part in which the stock 22 of the band severing blade 23 is movably disposed.

Spaced guide arms 24 and 25 extend from the member 20 as shown in Figure 7, and the stock 22 of the severing blade is slidable therebetween. The stock 22 is preferably formed with a vertical guide slot 26 to receive a threaded stop pin 27 extending from the member 20 and provided with a stop nut 28, to prevent the displacement of the stock 21 while at the same time leaving it free to be moved vertically.

At its upper end the member 20 is knife edged as at 29, while the cutter member 23 is also knife edged and inclined as shown at 30, the two knife edges co-acting to sever the binder member, as hereinafter explained.

Pivoted at 31 to the lever arm 19 is a shorter lever 32, the latter connected at 33

to the stock member 22 by a link 34 and pivot 35.

The lever 32 terminates in a hand grip 36, and is yieldably supported normally in its upper position by a spring 37.

By this means the member 22 is yieldably held in its upper position with the knife edges 29 and 30 of the band severing portion in inoperative or separated position.

10 At their outer ends the arms 24 and 25 are pierced to receive a pin 38 on which a cam supporting lever 39 is pivoted, the latter having a curved terminal 40 operative to limit its downward movement.

15 Attached to one side face of the lever 39 is a supporting bracket 41 in which a cam grip 42 is pivoted, the latter provided with an operating arm 43 externally of the bracket.

20 A stop device 44 is attached to the bracket 41 and provided with a toe element 45 beneath which the lever 43 engages when in its downward position, to hold the cam 42 in contact with the binder member and form a positive grip upon the latter, as hereafter explained.

25 The goods to be bound, for instance a bundle of parquetry elements as indicated at 46 in Figure 1 is placed upon the table 14 and against the side member 12. The binder element 47 in tape form, and preferably of thin 30 metal is supplied from a reel, indicated at 48, and first threaded between the grip cam 42 and the lever 39 thence between the knife edges 29 and 30 and thence entirely around the bundle 47 and the end of the tape ex- 35 tended for a short distance over the upper layer of the bundle as shown at 49 in Figure 1. By this means there are two thicknesses of the tape for a short distance on the upper face of the bundle, the friction of this 40 overlapping may be sufficient to prevent slipping when strain is applied, or the short portion 49 may be first secured to the bundle by a small nail or other means. When the tape is first applied the lever 39 with its grip cam 45 device is elevated to the required extent, and the grip cam moved to firmly clamp the tape to the lever 39 so that when the lever 39 is moved downward, a strong strain will be applied to the tape to bind it firmly around the bundle. When this is accomplished, the 50 tape will be secured to the bundle by applying a suitable fastening means such as one or more small nails driven through the overlapping portions of the tape at 49. The lever 36 is then operated to cause the cutter member 23 in coaction with the knife edge 29 to sever the tape and release the bound bundle. This machine develops a speed of about eighty bundles to the hour, and the force applied on the tape is so great that with small exertion on the part of the operator the tape can be pulled apart.

The angle at which the cutting knives are ground and the simplicity of construction makes the cutting of the tape very easy.

The weight of the machine is about one hundred and fifty pounds, and may be secured to the floor by lag screws or other means and can be easily shifted from place to place.

Having now described my invention, that which I claim to be new and desire to protect by Letters Patent, is:

1. A baling machine comprising a stand, a stretcher bar pivoted thereon, a tape cutter 75 slidable upon the bar, a lever pivoted upon the bar and connected with the cutter, a spring for returning said lever, a second lever pivoted upon the bar and a tape gripping means pivoted upon the last mentioned lever. 80

2. A baling machine comprising a stand, a stretcher bar having angularly disposed ends pivoted thereon, a cutter slidably mounted upon the bar, a lever pivoted upon the bar and operatively connected with the cutter, a spring for returning said lever, a second lever pivoted upon the bar and having an end adapted to engage the bar and a tape gripper mounted upon the second mentioned lever. 90

3. A parquetry baling machine comprising an adjustable stand and a baler carried by said stand, said device including a pivoted bracket to which said baler is attached, said baler comprising a pivoted tape stretching 95 lever fixed to said plate, a cutting device for said tape, a link for operating said cutting device, and a spring controlled lever for operating said link, said first lever carrying a 100 tape holding eccentric.

4. In a device of the character described comprising an adjustable stand and a frame therefor, a rod carried by the frame and a baling mechanism comprising a tape control, means for stretching the tape and a tape cutting mechanism. 105

5. In a device of the character described comprising an adjustable stand and a frame therefor, a rod carried by the frame and a baling mechanism comprising a tape control, means for stretching the tape and a tape cutting mechanism, said cutting mechanism being lever operated and spring controlled. 110

6. The device as claimed in claim 5, said means comprising a lever. 215

7. The device as claimed in claim 5, said means comprising a lever, upon which the tape control is carried.

8. The device as claimed in claim 5, said means comprising a lever, upon which the tape control is carried, said last lever being hand operated. 120

9. The device as claimed in claim 5, said means comprising a lever, upon which the tape control is carried, said last lever being hand operated, said tape control comprising a tape holding eccentric. 125

10. The device as claimed in claim 5, said means comprising a lever, upon which the tape control is carried, said last lever being 130

hand operated, said tape control comprising a tape holding eccentric, said eccentric being lever operated.

11. A parquetry baling machine comprising an adjustable stand and a baler carried by said stand, said device including a pivoted bracket to which said baler is attached, said baler comprising a pivoted tape stretching lever fixed to said plate, and a cutting device for said tape, a link for operating said cutting device and a spring controlled lever for operating said link, said first lever carrying a tape holding eccentric, said eccentric being lever operated.

15 In testimony whereof I affix my signature.
LEWEY C. CARROLL.
